UNITED STATES PATENT OFFICE.

FRANK MUNSON, OF BUCHANAN, MICHIGAN, ASSIGNOR TO THE BUCHANAN MANUFACTURING COMPANY, OF SAME PLACE.

FOLDING BED.

SPECIFICATION forming part of Letters Patent No. 336,525, dated February 16, 1886.

Application filed April 15, 1885. Serial No. 162,307. (Model.)

To all whom it may concern:

Be it known that I, FRANK MUNSON, of Buchanan, in the county of Berrien and State of Michigan, have invented new and useful improvements in Folding Beds; and I do hereby declare that the following is a full, clear, and exact description thereof, reference being had to the accompanying drawings, which form a part of this specification.

This invention relates to a new and useful improvement in folding beds, and it refers more particularly to that class which fold upwardly in the center of the rails.

My invention consists, first, in the facilities I have provided for parting the bed into sections, so that it may be moved through openings or passages otherwise too narrow to move the whole bed; second, in rendering the operation of folding and unfolding more automatic by the peculiar arrangement of strong coil-springs; third, in arranging the parts so that a spring bed-bottom of ordinary construction and secured in the ordinary manner may be used, dispensing with all special tension devices for the mattress; fourth, in the peculiar arrangement of certain parts, whereby greater stability of the head and foot boards in folding and unfolding is secured; fifth, in the improved construction of the rail-joint; sixth, in the improved manner of hinging the cover; and, seventh, in the peculiar construction of the head and foot boards.

In the accompanying drawings, which form a part of this specification, Figure 1 is a vertical central section through my improved bed as folded. Fig. 2 is a similar section with the bed unfolded.

A is the head-board, B is the foot-board, C are the rail-sections, and D is the hinged cover, of a folding bed, the rails of which are arranged to fold upwardly in the center, allowing the head and foot boards to approach each other and form, when the rails are completely folded and the hinged cover dropped in place, a compact case having the outward appearance of a desk.

The construction and arrangement of the different parts to which my invention refers are as follows:

G are cross-rails secured between the ends

of the side rails, and E is a spring bed-bottom consisting of a series of helical or coil springs connected together on top by wire loops, and secured on the bottom upon a series of cross-slats, F. The ends of this bed-bottom are secured to the cross-rails G, and the sides may be secured, except near the middle, to the side rails. The slats upon which the springs rest are secured to the side rails, and are flush with them on the under side. The outer ends of the rail-sections are pivotally secured at a to the head and foot board, respectively, and their inner ends are pivotally secured at b b to a saddle, H, which serves as an intermediate connecting-rail and protects the joint between the rail-sections on the sides and on top.

I is a circular piece firmly secured to the saddle midway between the pivotal points b b of the rails. It is cut away on top, so as to form a flat shoulder, c. The inner ends of the rail-sections terminate in square shoulders J, ogee-shaped shoulders K, and intermediate shoulders, L. The shoulders J squarely abut against each other when the bed is extended, while the shoulders L at the same time seat themselves against the top of the circular piece I. The ogee-shaped shoulders K are partly seated against the circular piece I when the bed is extended, and when it is folded they keep contact with it and guide and support it, relieving thereby the pivot-pins b from strain.

The shoulders J form a large portion of the ends of the rail-sections, and they therefore form, when tightly pressed against each other, as is done by the action of the coil-springs, hereinafter described, a strong rail-joint when the bed is extended, and which opens easily in an upward direction, owing to the little friction with which the shoulders K travel on the rounded piece I. This arrangement of joint firmly guides the parts by frictional contact in folding and unfolding without weakening the rail ends.

The outer ends of the rail-sections are rounded, forming a segment of a circle with the center in the pivot a, and curved tracks M of the same radius are formed on the head and foot boards, respectively, for these rounded

ends to abut against in folding and unfolding. These tracks M terminate on top in overhanging shoulders or stops N, which, in connection with shoulders h on the ends of the rails, 5 limit the movement of the rail in unfolding, so that it cannot drop further in the middle than is desired.

O are strong coil springs, placed near the head and foot boards, respectively, and arranged lengthwise of the bed. They are secured in position by means of a strap-iron, P, which is screwed to the cross-rail and terminates in an eye, d, through which the tension-rod Q passes. The latter terminates on one 10 end in a hook, e, to which one end of the cable R is secured, while the opposite end carries a roller, S. It is also provided with a collar or flange, f. The coil-spring O is interposed between the eye d and the flange f, and the cable 15 R connects the tension-rods of the two coil-springs.

T are curved tracks, eccentrically to the pivots a, and adapted for the rollers S to travel on. These parts are so arranged that when 20 the bed is extended the coil-springs are under strong tension, occasioned by the limited length of the cable R, which operates to firmly draw the rail-sections together endwise, making the rail-joint rigid under the action 25 of the weight of the bed-clothes, rails, and bed-bottom. As soon as the operation of folding the bed begins, however, the parts approach each other, and the cable R (which is free to drop a little) gradually relieves the 30 tension of the coil-springs, leaving them, however, under enough tension to counterbalance the weight of the parts which have to be lifted up.

While the operator lifts the rails in the 35 center in the first operation of folding the bed the rollers S travel on the tracks T, without, however, deriving any more tension therefrom than is due to the cable, the object being merely to thereby steady the foot and head boards and 40 prevent them from tipping, which in the present construction of these folding beds is very liable to occur during the operation of folding. As soon as the side rails are folded up sufficiently, the operation of folding the bed is 45 completed by pushing the foot-board against the head-board, and during this stage of the operation the cable R becomes slack, as the tracks T, instead of accommodating themselves any further to the expanding springs, begin 50 to compress them by pushing the tension-rods Q inwardly.

One object of getting the cable slack is to prevent the coil-springs from opposing their 55 tension to the closing together of the parts. Another object is to allow of the bed being divided in sections, in the manner hereinafter described.

I preferably use but one pair of coil-springs, O, which I arrange in the longitudinal center 60 of the bed; but, if desired, more springs may be used.

In other folding beds of this kind the bed-

bottom is made use of as a counter-balance by putting it under a strong tension by the elbow-leverage of the side rails in unfolding. 70 In my invention, there being no such arrangement required, I am enabled to use a spring bed-bottom of ordinary construction instead of a wire mattress, or a spring bed-bottom of such special construction which will admit of 75 being put under tension, and which requires special devices designed to relax the tension of the mattress or spring bed-bottom when folded.

In order to adapt the bed to be taken into 80 sections, I provide the pivots b of the lower rail-sections with slots l, and make the center row of loops, k, of the spring-bottom so as to unhook at one end.

If it is desired to divide the bed into sections, fold it and then unhook the center row of loops, k, so as to separate in two the spring-bottom. This divides the bed in two, except the cable, which can be unhooked from either 85 one of the eyes e.

The cover is so constructed as to swing clear up or down. This I accomplish by providing the head-board with corner-posts, to the inner sides of which I secure the stationary part of a suitable hinge, W, which throws the cover 90 sufficiently forward to give it, when thrown up, a reclining position. The space between the hinged end of the cover and the head-board is suitably closed by a ledge projecting from the head-board. This arrangement of cover 95 allows it to be thrown open for ventilating the bed.

What I claim as my invention is—

1. In a folding bed, as described, the rail-sections having slots at their central meeting-points, combined with a connecting-piece having pivots engaging said slots, substantially as, and for the purpose specified.

2. In a folding bed, substantially as described, the rail-sections having the slots l at their central meeting ends, combined with the saddle having pivots fitting in said slots, as set forth.

3. In a folding bed of the kind described, the coil-springs O, secured upon opposite ends 115 of the folding-bed bottom, and connected by a tension cord or cable, substantially as described.

4. In a folding bed of the kind described, the coil-springs O, secured upon opposite ends 120 of the folding-bed bottom, and each provided with tension-rods Q, terminating in eyes e, and a connecting tension cord or cable, R, detachably secured thereto, substantially as described.

5. The coil-springs O, secured upon opposite ends of the folding-bed bottom and provided with tension-rods Q, connected by a rope or cable, having rollers S secured to their outer ends, in combination with the tracks T, 130 all arranged to steady the head and foot boards in folding, substantially as described.

6. The coil-spring O, secured upon opposite ends of the folding-bed bottom and provided

with tension-rods Q, connected by a rope or cable, and having rollers S, secured to their outer ends, in combination with the tracks T, so arranged as to compress the springs at the close of the folding, substantially as described.

7. In a folding bed, as described, the combination, with the rail-sections having open-ended slots, of an intermediate connecting rail engaging said slots and detachably connecting the sections together and protecting the joint between the same, substantially as described.

8. The folding rail-sections C, provided with elongated slots at their central meeting-points and terminating at their inner ends in ogee-shaped shoulders K, in combination with the saddles H, pivotally secured in the slots in the inner ends of the rail-sections and pro-

vided with the rounding piece I, arranged between the shoulders K, all arranged to guide the parts in folding by frictional contact, substantially as described.

9. The folding rail-sections C, provided with the slots l, as described, and terminating at their inner ends in shoulders J, L and K, arranged as described, in combination with the saddles H, pivotally secured in the slots in the inner ends of the rail-sections and provided with the rounding piece I, having the shoulders c formed on it, substantially as described.

FRANK MUNSON.
